MATRIX COMPOSING AND LINE CASTING
MACHINEChristian Augustus Albrecht, Berlin, Germany,
assignor to Mergenthaler Linotype Company,
Brooklyn, N. Y., a company of New YorkApplication August 7, 1936, Serial No. 94,752

12 Claims. (Cl. 199—50)

This invention relates to typographical slug casting machines.

In matrix composing and line casting machines, it has already been proposed, when casting short lines of characters upon a longer slug body, to provide for that portion of the slug which is devoid of characters to be lower than the regular height appropriate to the casting mould, so as to obtain sufficient space for mounting printing plates. For this purpose, it has already been proposed to make the whole casting mould lower, that is, just high enough to correspond with the height of the slug portion which is devoid of characters, and to increase the height of the character-bearing slug portion by means of a special intermediate member inserted between the casting mould and the matrix line, which member, in the case of regular matrices correspondingly extends the mould slot, but is filled up by special lugs on the spacers. For quadding out that portion of the slug devoid of characters, special hand spacers in the form of matrices are therefore needed. On the other hand, the said method is not practicable when the slug portion devoid of characters is cast in the manner heretofore proposed against the vise jaws.

It has also heretofore been proposed to cast the slug portions devoid of characters much lower, by arranging for the mould cap to be movable relatively to the mould body, and to fasten to the vise jaws, a core member adapted to enter the mould when the mould is closed up against the said core member and thus reduce the height of the slug. Owing to the necessity of having a movable mould cap, this arrangement is difficult to operate, and metal squirts can easily result through inadequate closure of the cap.

The present invention provides a very simple construction which does not present the disadvantage of having a mould with relatively movable parts but which is still capable of use in combination with automatic quadding or centering of short lines. For this purpose, according to the invention, there are provided in combination with a low slug mould sliding members attached to the vise jaws, adapted to overlap the space between the jaws in order to form a slot extending the casting slot to the customary depth, while the slot of the mould beyond the inner faces of the jaws will be covered up.

One constructional form of the invention is illustrated in the drawings, wherein:—

Figure 1 is a front elevation of part of the

mould disc with the mould and the clamping jaws located in front of the latter;

Figure 2 is a plan of Figure 1;

Figure 3 shows separately the means for adjusting the slug height, as seen from the front; 5

Figure 4 is a vertical section through a portion of the mould disc, the mould and the vise frame;

Figure 5 shows, on a larger scale, the bolt for locking the vise to the machine frame, modified 10 for carrying out the invention;

Figure 6 is a section through the mould and the means for adjusting the slug height in the position wherein the left-hand vise jaw closes 15 the mould slot, and

Figure 7 a similar view showing the position when the mould is closed by the right-hand jaw;

Figures 8, 9 and 10 illustrate slugs which can be produced with the arrangement according to the invention, for lines of characters centred or 20 as the case may be quadded out to the left and to the right;

In the drawings, 1 is the mould disc, which carries, in known manner the moulds 2. The arrangement and the attachment of the mould on the mould disc, are as customary, except that the moulds are shallower than demanded by the required height of the characters, and the depth of the mould slot being such that blank slugs or blank portions of slugs cast therein will be 30 only as high as is necessary to permit printing plates to be mounted thereon. In front of the mould are located two vise jaws 3 and 4 which are adapted to bear, in the customary manner, against each end of the line of matrices. The 35 jaws are not, as is customary, rigidly secured to the supports 5 and 6 by which they are moved inwardly and outwardly, but are forwardly and backwardly displaceable relatively thereto. In such displacement the jaws are guided by studs 40 or pins 7 which are secured to the vise jaws and are adapted to slide in corresponding openings in the supports 5 and 6, and by studs 8 which are screwed to the supports 5 and 6, and pass through openings in the vise jaws 3 and 4. 45

Springs 9 encircling the studs 8 press the vise jaws 3 and 4 away from the supports 5 and 6, and consequently hold them normally in the position in which they are shown in Figure 2. A sliding member 10 is attached to the left vise jaw 3, and a sliding member 11 is attached to the right vise jaw 4. These sliding members are connected to the vise jaws by means of screws or in any other preferred manner and take part in the longitudinal movement of the jaws. Cross 55

- sections through the sliding members are shown in Figures 6 and 7, which are drawn to a larger scale. That portion of each sliding member which extends along the face of the respective 5 jaw is substantially L-shaped in cross section, Figure 3, having a horizontal portion or shank guided by a horizontal surface on the mould, and a vertical portion or shank located in front of the mould.
- 10 The sliding members are reduced in height at the portions thereof which project inwardly between the inner faces of the vise jaws, and the reduced portions are so offset relatively to each other, that when they overlap in the manner 15 shown in Figure 3, a slot 12 will be formed between them, the said slot registering with the mould cap in use. The depth of the vertical shanks of the sliding members 10 and 11, i. e., the dimension in the direction from the front to 20 rear of the machine, added to the depth of the mould and of the formative cavity on the matrix, gives full type-height to the characters on the slug. As shown in Figure 4, the slot 12 is located in front of the mould slot 13, and constitutes 25 therewith a casting slot of the normal depth, so that a matrix held between the clamping jaws 3 and 4 in front of the said casting slot will produce characters of the regular type-height.
- The two vise jaws 3 and 4, are so controlled 30 in known manner by their supports 5 and 6, that, according to the adjustment of the machine, either centring or quadding out at either end of the line can take place. The devices used for this purpose are already known; they are therefore 35 not represented in the drawings and need not be described here in detail.
- For the maximum length of line for which the mould is used, the jaws 3 and 4 have the position shown in Figure 2, the slot 12 formed by the two 40 sliding members 10 and 11 having its maximum length. In this position full length normal height slugs can be cast. If a short line is required, and is either centred or quadded to one side or the other, one of the two jaws 3 and 4 will 45 be moved towards the other, or both jaws towards each other. The sliding members 10 and 11, being fast to the clamping jaws, will thus be taken with them and the slot 12 will be made correspondingly shorter, and indeed reduced to the length 50 appropriate to the composed line of matrices. It is only at those places where matrices are present in the line that the cross section through the mould and the sliding members will have the appearance represented in Figure 4; on the other hand, at the right, or at the left of the composed 55 matrices, a section through the mould and sliding members will appear as shown in Figures 6 and 7, Figure 6 being a section at the left of the composed line and Figure 7 a section at the right of the composed line. It is evident that here the vertical shank of the sliding member 10, or 11, will cover the casting slot of the mould. The blank portion of the slug cast at those places will 60 therefore be reduced in height. The slugs will 65 thus have the appearance shown in Figures 8, 9 and 10, so that when appropriate number of such slugs are placed side by side, a space or spaces for receiving printing plates will be provided.
- As customary, the vise frame is locked in its 70 closed position by two bolts 15, which form a bayonet joint with two recessed bolts 14 on the machine frame. When the right jaw 4 is in the extreme right position, the sliding member 11 would come into contact with the respective locking bolt on the machine frame. It is therefore

necessary, as shown in Figure 5, that the recessed bolt 14 mounted on the machine frame at that side be cranked so as to provide sufficient space for the passage of the sliding members 10 and 11. 16 is the vise frame in which are mounted the 5 15 supports 15 and in which are also guided the supports 5 and 6 for the clamping jaws.

The mode of operation of the machine is as follows:—

The line is composed in the usual manner and 10 then transferred to the first elevator 17 (Figure 4). The first elevator descends and thereby brings the line between the two clamping jaws 3 and 4. There is no difficulty about this because the two sliding members 10 and 11 on the 15 clamping jaws 3 and 4 are retracted by the springs 9 from the supports 5 and 6. As soon as the line is positioned between the clamping jaws the latter move as is customary towards the line and clamp it between them. After the justification 20 operation has taken place, the metal pot is moved into contact with the mould, and presses the latter against the two sliding members 10 and 11 which, by the closing of the clamping jaws have themselves been closed up to such an extent that they 25 leave the mould slot free only at those places where character matrices are present, and cover the mould slot elsewhere. When the mould advances towards the line of matrices, it comes into contact with the sliding members 10 and 11 and 30 presses the latter and the clamping jaws connected therewith forwardly against the action of the springs 9, so as to bring the sliding members into contact with the line of matrices. The casting operation then takes place and results in 35 the production of a slug according to one of the forms shown in Figures 8, 9 and 10, whereupon the mould moves backwards. When the mould moves back the latter will first take with it the cast slug and the sliding members 10 and 11 40 as well as the clamping jaws 3, 4, until the movement of the clamping jaws is arrested by the heads of the studs 8. The mould then moves back a little more and pulls the slug out of the slot 12 between the two sliding members 10 and 45 11. In this position the cast slug rests at one side of the sliding members 10 and 11 and the line of matrices is free on the other side thereof. The mould disc can now be rotated in the usual manner in order to bring the slug into ejecting 50 position, and the first elevator moves upwardly with the line of matrices in order to transfer the latter to the distributing mechanism.

It must be understood that the invention is not limited solely to the constructional form described above, since various modifications thereof may be introduced as they become necessary or desirable under different conditions and requirements which have to be fulfilled, without departing from the scope of the invention.

Having described my invention, I declare that what I claim and desire to secure by Letters Patent is:—

1. A method of forming a typographical slug from a line of matrices presented to a mould slot 65 of sub-normal depth, in which the body of the slug is cast, wherein the effective depth of the slot at the part thereof to which the matrices are presented is increased automatically in accordance with the length of the matrix line.
2. A method of casting a typographical slug from a line of matrices presented to a slotted mould of sub-normal depth, which includes the step of automatically increasing the effective depth of the slot at the part thereof to which 75

the matrices are presented, and simultaneously covering and closing the remainder of the mould slot.

3. A typographical slug casting machine comprising a mould embodying a mould slot of sub-normal depth, jaws adapted to clamp a line of matrices for presentation to the mould, and movable means positioned between the jaws and the mould adapted to cover the mould slot over those portions not confronted by matrices, and to provide a slot of increased depth over the length in front of the matrices.

4. A typographical slug casting machine comprising a mould embodying a mould slot of sub-normal depth, jaws adapted to clamp a line of matrices for presentation to the mould, and means positioned between the jaws and the mould and movable with the jaws to cover the mould slot over those portions not confronted by matrices and to provide a slot of increased depth over the length in front of the matrices.

5. A typographical slug casting machine comprising a mould embodying a mould slot of sub-normal depth, jaws adapted to clamp a line of matrices for presentation to the mould, and members secured to said jaws and extending between the jaws and the mould, adapted to close the slot over portions not confronted by matrices and to provide a slot of increased depth over the length in front of the matrices.

6. A typographical slug casting machine comprising a mould embodying a mould slot of sub-normal depth, jaws adapted to clamp a line of matrices for presentation to the mould, an L-shaped member on each jaw, between the jaw and the mould, extending towards the other jaw, said L-shaped members overlapping one another so that a slot of constant width is provided by the L-shaped members between the jaws, and the length of this slot, is varied as said jaws close on the matrix line.

7. A typographical slug casting machine according to claim 6, wherein said L-shaped members close the mould slot over those parts adjacent to the jaw faces and provide an additional depth of slot in front of the matrices.

8. A typographical slug casting machine according to claim 5, wherein the jaws upon which

said members are movably secured, are movable towards and away from the mould, and are spring urged towards the mould against limiting stops.

9. In a typographical slug casting machine a casting slot formed by a normal length mould slot of low depth, built out depthwise by an auxiliary slot, in register therewith, of substantially the same length as the matrix line, said auxiliary slot being formed by members on the matrix clamping jaws, which also cover and close the low depth mould slot where it is not confronted by matrices.

10. In or for a typographical slug casting machine, a mould comprising a slotted main body part and a slotted auxiliary face part, the two said parts being arranged to register with each other and to provide a mould slot of full depth, said auxiliary face part being made up of members which are movable relatively to each other and to the main body part to vary the length of the auxiliary mould slot with reference to the main mould slot.

11. In or for a typographical slug casting machine, a mould comprising a slotted main body part and a slotted auxiliary face part, the two said parts being arranged to register with each other and to provide a mould slot of full depth, said auxiliary face part being made up of members which are movable relatively to each other and to the main body part to vary the length of the auxiliary mould slot with reference to the main mould slot, and each of said members constituting a side and end wall of the auxiliary mould slot.

12. In a typographical slug casting machine, the combination of a mould comprising a slotted main body part and a slotted auxiliary face part, the two said parts being arranged to register with each other and to provide a mould slot of full depth, and a pair of matrix line clamping jaws movable toward and from each other to accommodate matrix lines of different lengths, said auxiliary mould part being made up of members movable with the clamping jaws to vary the length of the auxiliary mould slot with reference to the main mould slot in accordance with the length of the matrix line.

CHRISTIAN AUGUSTUS ALBRECHT.
